UNITED STATES PATENT OFFICE

JOHN G. SHODRON, OF FORT ATKINSON, WISCONSIN, ASSIGNOR TO JAMES MANUFACTURING COMPANY, OF FORT ATKINSON, WISCONSIN, A CORPORATION OF WISCONSIN

METAL WEATHER SHIELD FOR DOORS AND WINDOWS

Application filed March 6, 1929. Serial No. 344,640.

My invention relates to improvements in metal weather shields for doors and windows. The primary object of my invention is to provide a substitute for ordinary weather stripping which is peculiarly adapted for use in connection with sheet metal doors, door frames and window frames and sash composed of sheet metal for the reason that my improved shields are so formed as to constitute a portion of the frames and sash or other members to which they are applied.

Further objects are to provide shields which may be utilized to protect and enclose marginal portions of window frames and the putty or equivalent material employed to hold the panes in place, while also forming a weather proof covering for the joints between the sash and its supporting frame; to provide means whereby a strip along the margin of a door may be utilized to not only protect such margin but to form a weather proof joint in association with counterpart members on the door jamb; to provide shields which are adapted to receive and support bodies of fibrous material in cooperation with counterpart shields which seat against such fibrous material and protect it from the elements; to provide metallic shields adapted generally to form weather proof joints and also protect from the elements and other destructive agencies bodies of yielding or frangible material such as strips of fiber, putty, etc. whereby their qualities may be permanently preserved.

A further object of my invention is to devise a metal window frame and sash frame structure in which what may be conveniently termed the beam elements are reinforced by ledge forming and joint covering elements in such a manner as to provide the necessary resistance to bending and torsional strain, whereby the entire structure may be formed from sheet metal of sufficiently thin gauge to be easily workable, and without excessive weight, while possessing the necessary strength and durability with the added advantages obtained in wooden structures only by rabbeting the wooden bars to form ledges and adding to such bars weather stripping attachments.

In the drawings:

Figure 1 is an elevation of a combination window and door poultry house structure to which my invention has been applied.

Figure 2 is a sectional view on an enlarged scale taken on line 2—2 of Figure 1.

Figures 3, 4 and 5 are additionally enlarged fragmentary sectional views taken on lines 3—3, 4—4 and 5—5 of Figure 1.

Figures 6, 7 and 8 are fragmentary sectional views corresponding with Figures 3, 4 and 5, with modifications adapting my invention to a hinged window structure.

Like parts are identified by the same reference characters throughout the several views.

In Figures 1 to 5, inclusive, my invention is illustrated as applied to a combination poultry house window and poultry exit door of the type illustrated in Figure 1, wherein the poultry exit door 20 is surrounded on three sides by panes of glass 21 mounted in a metallic sash 22 having a cross rail 23 to which the door is connected by a set of hinges 24. The door is held in various positions of adjustment by suitable mechanism forming the subject matter of a separate application bearing even date herewith and which includes the door adjusting lever 25, an operating rod 26 linked thereto and a rod retaining device 27. The mechanism for adjusting and holding the door in various positions forms no part of the invention herein disclosed and further description thereof is therefore deemed unnecessary.

Referring to Figure 3 it will be seen that the cross rail 23 comprises a strip of metal to which is attached one leaf 30 of each hinge 24. The upper margin of the cross rail strip 23 is provided with an inwardly projecting member 31 perpendicular to the outer face of the rail 23 and having an upturned flange 32 at its inner margin which serves as a seat for one of the panes of glass 21. The seating is similar in form and function to the rabbeted shoulder ordinarily formed in a wooden sash, with the exception that the metal flange 32 is provided with an oblique upwardly turned marginal portion 33 which may abut directly against the pane of glass and form a pocket to receive a body

of putty 36 which extends around the margin of the pane and connects with a body of putty 37 having the usual triangular form and employed to retain the pane 21 in secure anchorage to the seating formed by the flange 32.

The oblique outer face of the body of putty 37 is covered by a thin sheet metal plate 39, held in position between two retaining strips 40 and 41 which overlap the side margins of the plate 39 as clearly shown in Figure 3. The retaining strip 41 is preferably formed with arms 42 extending inwardly along the surface of the sash rail member 31, and through slots 43 therein for anchorage thereto. These arms 42 may be extended along the pane and connect with the strip 40 to support the latter. Each strip 40 has its ends abutting and may be connected with corresponding retaining strips disposed along the associated sash rails at the side of the pane.

In the construction shown, the door is composed of a sheet of fibrous material 43' having sheet metal inner and outer walls 44 and 45 to completely conceal and protect the fiber. The wall 44 has its upper margin outwardly turned across the upper margin of the fiber sheet as indicated at 46 and this portion 46 has an upwardly turned marginal flange 47, over which a portion 48 of the outer wall 45 extends. The upper margin of the portion 48 is reversely folded over the flange 47, with a downwardly turned lip 49 bearing upon the inner surface of said flange. The portion 48 is interposed between the flange 47 and the sash rail 23 and bears against the under surface of the latter when the door is in the closed position.

It will be understood that the terms "upwardly", "downwardly", "outwardly" and "inwardly" as used in this description are used relatively and with reference to the specific structure illustrated in the drawings, in which the door is suspended from its upper margin by the hinges 24 although it occupies an oblique or inclined position when fully closed. The location of the hinges and the position of the door with reference to its supports and door jamb are merely incidental to the specific structure illustrated and the terms used are employed merely for the purpose of description with reference to the particular embodiment of my invention as applied to a poultry house.

At the lower margin of the door, its inner sheet metal wall 44 is outwardly turned to form the fiber covering member 55. The latter has a downwardly turned inclined flange 56 which is covered by a correspondingly inclined extension portion 57 of the outer wall 45. The extension 57 is folded upon itself at 58 and provided with an obliquely positioned margin 59 parallel with and bearing upon the inner face of the flange

56 to anchor the latter securely to the outer wall 45 of the door. The folded portion 58 overlaps the metal door frame plate 60 which is folded upon itself to form a door sill 61 and a door jamb 62. A strip of resilient sheet metal 63 is secured to the inner sheet metal wall 44 with a depending portion 64 obliquely disposed, with inward inclination, and adapted to bear upon the jamb member 62 when the door is closed. (Fig. 4).

At the sides of the door (Fig. 5) similar strips of resilient sheet metal 67 are employed which seat against flanges 68 connected with folded strips of sheet metal constituting sash rails 69 which support window panes 21 at the sides of the door. One margin of the folded strip of metal forming the sash rail 69 serves as a rabbet or shoulder flange 70, similar to the flange 32, with bodies of putty 36 and 37 embracing margin of the pane and covered by a protecting shield 39 secured as set forth in the description of Figure 3. The side margins of the inner wall 44 of the door are bent to form the fiber coverings 71 which have outwardly turned flanges 72 covered and infolded by extension portions 73 of the outer wall 45 of the door.

It may be assumed that all of the window panes shown in Figure 1 are secured to the respective rails of the sash substantially as illustrated in Figures 3 and 5, the putty being covered in each case by a sheet metal shield. The marginal rails 75, however, are provided with comparatively wide extension flanges 76 which overlap the boarding or other wall members 77 and are partially interposed between such wall members and an outer covering 78 to form a water tight joint, as shown in Figure 2.

From the above description of Figures 1 to 5, inclusive, it will be observed that metallic water and air tight joints are provided for both the window and the door and for each pane of the window. The putty being covered by the sheet metal shield, it is less liable to crack and break away than would otherwise be the case and in any event all defects are concealed by an impervious metal covering. At the door hinge joint the sash rail 23 overlaps the extension 48 of the outer wall of the door and forms therewith a weather tight joint. Similarly, the sides and bottom of the door have projecting flanges which overlap the sash rail and door respectively and form weather proof joints of the same general character as that at the hinged margin, with the additional protection afforded by the resilient metal shields 67 and 64, shown in Figures 4 and 5, respectively.

In Fig. 3 the member 31 constitutes the beam or beam member of the cross rail. Its resistance to strain, being principally exerted in a plane perpendicular to the plane of the

window glass and the strength of the sash frame to resist external and internal air pressure, is usually dependent upon the depth of the beam, i. e. the width of the strip of metal 5 composing the member 31. But it is obvious that unless this strip is made of excessive thickness and objectionable weight it would be only slightly resistant to transverse stresses or torsional stresses. Therefore the members 10 23 and 32 are important as reinforcing members independently of their other functions.

The flange 23 constitutes the visible portion of the rail as viewed from the exterior. It has great strength as a hinge supporting 15 member from which the door may be hung and it prevents the outer margin of the strip 31 from yielding torsionally or from bending or yielding in a plane parallel to the plane of the pane of glass.

20 The ledge member 32 performs a similar function along the inner margin of the beam member 31, in addition to its functions of a glass supporting ledge and a cavitated device for pocketing a body of putty against which 25 the margin of the pane of glass may be seated to protect the glass from fracture against the metal surface of the ledge and also provide a perfect air tight joint closure.

In addition to these functions the portion 30 23 provides an over-hanging member underneath which the joint closing member 48 may swing. This portion 48, its reversely folded portion 49 and the engaged portion 47 of the door similarly reinforces the upper margin 35 of the door and its beam member 46 in addition to the function of forming an air tight closure against the member 23 when the door is closed.

40 The same principle is invoked in the structure of the other rails of the sash and window frame although in some instances additional reinforcement is obtained by folding the beam member such as the member 69 shown in Fig. 5, this member being folded and provided with oppositely disposed ledges one of 45 which serves as a jamb for the door or for the resilient sheet metal strip 67 connected with the door, whereas the other flange forms the rabbeted shoulder 70 having the triple 50 purpose of providing a ledge for the window frame, a reinforcement for the beam, and a putty receiving cavity whereby a body of putty may be placed underneath the glass.

55 In Figures 6 to 8, inclusive, I have illustrated an embodiment of my invention as it is applied to a hinged window sash. The construction is so similar to that above described with reference to the combination door and window that the same reference letters will be employed for the corresponding parts with the letter "a" added. It is desirable to embody slight modifications in the window structure in order to produce more effective air tight joints than it is possible to provide for a door through which

the fowls must pass. The hinged windows are usually located at higher levels and it is desirable to prevent the escape of warm air which develops more or less internal pressure in the upper portions of the room or building 70 These and other requirements are satisfied by the additional features in Figures 6, 7 and 8 now to be described.

At the upper side of the window a roof plate or wall plate 76^a is employed and this 75 is extended underneath the covering 78^a in a manner similar to that illustrated in Figure 2, but preferably with a gutter plate 80 interposed and provided with an upwardly or outwardly projecting flange 81 which 80 forms the lower wall of the gutter. Its outer or upper margin is preferably in the form of an open bead 82 to re-enforce the gutter and also to prevent water from splashing or 85 washing over the flange 81.

It will also be found desirable to fold the plate 76^a upon itself to form a window supporting cross rail 23^a, similar in function to the cross rail 23 shown in Figure 3. By folding the sheet metal extension of the sheet 76^a, 90 a re-enforced cross rail is provided upon which the hinge 24^a may be mounted. The folded portion of the sheet is inwardly turned to form an inwardly projecting member 84 and this has a marginal flange 85 which extends parallel to the cross rail 23^a on the inner side and the members 85, 84 and 23^a constitute 95 a channeled beam within which a weather shield member 47^a connected with sash rail 31^a may be housed. This shield member 47^a, 100 is preferably provided with a divergent resilient sheet metal strip 86 which bears against the infolded portion of the cross rail 23^a at its upper or inner margin, its lower margin being secured in any suitable manner to the member 47^a. The hinge leaves 86 extend through apertures in the shield member 47^a and are secured to the sash rail 31^a. The shield 47^a and shield spring 86 provide 105 the window with a weather tight hinge joint 110 along its upper margin.

Along the lower margin of the window a sheet metal channeled beam 87 is preferably employed and provided with a folded strip of fibrous material 88 disposed with the folding line outermost and projecting slightly from the channel of the beam. The lower sash rail 31^a is provided with a perpendicular portion 89 having an inturned flange 90 which forms with the members 89 and 31^a a 115 channeled sash rail adapted to fit over the channeled beam 87 with the member 89 resting upon the fiber strip 88 whereby the latter serves as a packing for the joint, protected from the weather by the shield members 89 and 90 of the sash rail.

120 Along the sides of the window similar channeled beams 87 are employed and the side rails of the window sash are similarly formed with shield members 89 and 90 to 125

protect the packing strips and form weather proof joints similar to the lower joint of the window sash.

It will be understood that the embodiment of my invention disclosed in the drawings is peculiarly adapted for use in connection with windows and doors in the roofs of buildings and in inclined side walls of buildings. Examples of such buildings are illustrated in my former Patent No. 1,687,850, dated October 16, 1928, and in my co-pending application Serial No. 230,706, filed November 3, 1927. Therefore the weather shields are formed with regard to the direction of water flow and are calculated to carry water downwardly over the hinge joints and over the sills, lower panes or framing rails, with full protection when the windows and doors are closed.

By forming the window shields as a part of the sash rails and utilizing them in part to protect the putty and in part to protect the joints I provide a unitary structure which serves a three fold purpose. In poultry houses the putty not only requires protection from the elements but from the fowls who otherwise pick at puttied joints with their bills and take advantage of breaks or cracks to rapidly remove the putty from the window panes. The improved metallic weather shields protect the putty, tend to prevent it from cracking and give to puttied joints greater permanence than has been attained heretofore.

By forming my improved shields in counterpart members applicable to door and window frames on the one hand and to the sash margins or rails and door margins on the other I am able to satisfy the requirements for hinged windows and doors for barns, poultry houses, etc., more completely than has heretofore been deemed possible. In part my invention is not suitable to be applied to sliding windows and doors but insofar as it is applicable to the protection of puttied joints my invention may be used wherever such joints are found.

I claim:

1. A metal sash having a hinged supporting margin provided with a joint underlying flange and also provided with a flanged joint covering extension alongside the opposing margin.
2. A metal sash rail for inclined sash having at one side thereof a reinforcing putty and glass receiving ledge and at the other side thereof a joint covering flange forming, with the rail, a channeled member having its channel along its under side and adapted to fit over a counterpart member of a window frame.
3. A metal sash rail having at one side thereof a joint covering flange forming, with the rail, a channeled member adapted to fit over a counterpart member of a window

frame, in combination with a window frame having a beam like member off-set from the window frame and narrower than the channel in the channeled member whereby it is adapted to be received in said channeled member of the sash rail and provided with a fibrous packing rib for contact therewith.

4. A metal sash rail having a putty supporting cavitated reinforcing and glass receiving ledge along the inner margin of the rail on one side and a weather proof joint covering shield along the outer margin of the rail on the other side.

5. A metal sash rail for hinged window sash having a glass supporting rail reinforcing ledge along the inner margin of the rail on one side and a weather proof joint covering shield along the outer margin of the rail on the other side of channel shaped formation, disposed with the channel on the insideside.

6. A metal sash rail composed of a strip of sheet metal bent along longitudinal lines to form a central beam-like portion, the inner margin reinforcing portion adapted to constitute a pane supporting flange at one side thereof and an oppositely extending joint covering flange at the other side and along the outer margin thereof.

7. A metal sash rail having an integral pane supporting flange at one side thereof and along its inner edge margin and an oppositely extending joint covering flange at the other side thereof and along its outer margin in combination with a window frame having a counterpart flange disposed for interlapping contact with the joint covering flange on the sash, said flanges and rail being formed of a single strip of metal and the window frame and its flange being also formed integrally from a single strip of metal.

8. A metal sash rail having a pane supporting flange at one side thereof and an oppositely extending joint covering flange at the other side thereof in combination with a window frame having a counterpart flange disposed for interlapping contact with that on the sash, and a resilient metal strip interposed between said flanges to ensure pressure contact in substantially air tight relation.

9. A hinged closure structure of window and door type comprising the combination with a frame, of a closure having a margin hinged to said frame at one side and provided with a metallic plate extended beyond the opposing margin of the closure underneath the portion of the frame to which the closure is hinged.

10. A hinged closure structure of window and door type comprising the combination with a frame, of a closure having a margin hinged to said frame at one side and provided with a metallic plate extended beyond said margin of the closure underneath the

portion of the frame to which the closure is hinged, said frame having a metallic hinge supporting member in a plane exterior to the plane occupied by the outer surface of the closure whereby to provide space within which the closure plate may swing.

11. A hinged closure structure of window and door type designed for inclined frames for roof openings, comprising the combination with such a frame, of a metal plate secured thereto and extending downwardly over the upper margin of the opening, a closure provided with a covering plate hinged to the frame plate and having an upwardly projecting extension adapted for swinging movement underneath the frame plate between the closure and the upper margin of said opening, and interlapping weather-proof joint members along the other margins of the closure and frame respectively, disposed to allow free downward flow of water along the roof and across the enclosure.

12. A hinged closure structure of window and door type, comprising the combination with a frame having upper and lower metallic flanged members, the upper member having a hinge supporting extension substantially in the plane of the outer surface of the frame, a closure hinged to said extension and having a flange extending thereunder and normally substantially parallel thereto, whereby water may flow freely over the frame and closure without entry at the hinge joint.

13. In a hinged closure structure for openings in inclined roofing, the combination with such roofing and a covering therefor, of a frame for said opening having a metallic covering plate, and a flanged closure member extending from said plate underneath the roof covering whereby to allow water on the roof to flow freely across the joint formed by the closure with said frame without entering said joint.

14. In a hinged closure structure for openings in an inclined roofing, the combination with such roofing and a covering therefor, of a frame for said opening having a metallic covering plate, a flanged closure member extending from said plate underneath the roof covering whereby to allow water on the roof to flow freely across the joint formed by the closure with said frame without entering said joint, said closure having a similar flanged member in a lower portion thereof and a swinging closure member hinged thereto, and said swinging closure member being provided with a cover plate having a flanged extension at its lower margin normally covering the joint between it and said frame.

15. In a hinged closure structure of window and door type, the combination with a swinging margin of the closure, of a metallic channel shaped member arranged with the channel at the inner side and a relatively

fixed frame provided with a reversely positioned channel member off-set from the frame and having both side walls of the channel exposed and of a width adapted to be received within the channel of the first mentioned member.

16. In a closure structure of window and door type, a metallic frame member having flanges along its inner and outer margins extending in opposite directions, and a closure member provided with a normally oblique resilient metallic strip in normal pressure engagement with one of said flanges.

17. A hinged frame having a metallic member shaped to form a beam portion having a flange projecting outwardly from the frame along the outer margin of the beam portion, said flange having an inturned margin substantially parallel with the beam portion and forming therewith and with said flange an inwardly facing channeled member, in combination with a relatively stationary frame member having a reversely positioned channeled bar which, in width and in position, is adapted to have both its side walls received within the channel of the first mentioned channeled member, and a strip of packing material folded upon itself with its side margins embraced in the channel of the relatively stationary frame member to form a cushion and an air tight packing for the swinging frame member normally wholly enclosed and protected by the latter from the elements.

18. In a closure structure for roof openings, the combination with a marginal frame having an outwardly facing channeled bar, a cushioning packing seated in the channel of said bar and projecting therefrom, and a closure having an inwardly facing channeled member in which said channel bar and its packing may be received, whereby to protect the interior of both channels from the elements, the outer portions of said channeled bar and the projecting portion of its packing being disposed above the water shedding portion of the roof to which it is attached.

19. In a closure structure of window or door type, the combination with a marginal frame member having an outwardly offset and outwardly facing channel bar, of a closure member having an inwardly facing marginal channel in which the frame member channel bar may be received as to both side walls thereof to form a joint outwardly offset from the water shedding portion of the member to which the frame channel bar is attached.
